UNITED STATES PATENT OFFICE.

GUSTAF F. FRIBERG, OF CHICAGO, ILLINOIS.

HOUR-STRIKING TIME MECHANISM.

1,216,103.

Specification of Letters Patent. Patented Feb. 13, 1917.

Application filed May 18, 1916. Serial No. 98,293.

To all whom it may concern:

Be it known that I, GUSTAF F. FRIBERG, a citizen of the United States, residing at Chicago, in the county of Cook and State 5 of Illinois, have invented certain new and useful Improvements in Hour-Striking Time Mechanisms, of which the following is a specification.

This invention relates to hour striking mechanisms for clocks or time pieces. Its general object is to do away with the strike train of gears and its separate winding spring and let the going train, or time mechanism, automatically, during each hour, 15 provide sufficient power for the number of hammer blows required to strike one hour's time. This is accomplished in the present invention by means of a lever escapement under constant spring tension set by the 20 time mechanism during the half hour preceding each striking to escape the same number of teeth that blows are to be struck.

The invention consists in the novel construction, combination, and arrangement of 25 parts, all as hereinafter described in detail, illustrated in the accompanying drawing and incorporated in the appended claim.

In the drawing—

Figure 1 is a front view of the going 30 train of an ordinary clock, the parts which are old and well known being shown by dotted lines and my improvements in full lines.

Fig. 2 is a transverse section taken substantially on line 2—2 of Fig. 1 and omitting, for the sake of greater clearness, some of the details shown in Fig. 1.

Fig. 3 is a view of the striking mechanism alone being set preparatory to striking the 40 hour.

In Fig. 1 the steps formed on the involute curve of the usual "snail" —13— which determines the number of blows and which is fast on the arbor —14— of the hour hand —15— (Fig. 2), are labeled 1 to 12, inclusive. My invention is illustrated in connection with a common form of small alarm clock the bearing plates of which are supported on lugs 14' on a cast ring 15' to 45 which two of the feet or legs —16— are attached. Only the front bearing plate —17— attached to said cast ring, is shown, screws 18 indicating the connections for the rear plate, between which and the front 50 plate 17 that portion of the usual time mech-

anism with which this invention is not intimately concerned, is placed. As shown in Fig. 2 my improvement is arranged between the front bearing plate 17 and the hands of the clock, 19 representing the minute hand. 60

20 is the axis of the time mechanism driving spring, and of the main wheel, and its driving ratchet. The main wheel drives the center pinion which rotates on the minute hand arbor. The center wheel drives the 65 third pinion and third wheel, the second pinion being on the same axis as the first pinion but fast on the arbor 21 and indicated by the numeral 22 in Fig. 2. The third wheel drives the fourth pinion and fourth wheel, 70 the latter drives the escapement pinion, and the escapement wheel swings the balance wheel—23 in Fig. 1. Only the back gearing from the pinion 22, which drives the hour hand 15, is shown in Fig. 1, namely, 75 the wheel 24 driven by pinion 22 and carrying a pinion 25 which rotates the hour wheel 26 that is loosely mounted on the arbor 21. The power for setting my striking mechanism is taken from the wheel 24 80 through a pinion 27, which pinion is the only toothed wheel added to the trains of gears of the ordinary clock.

Referring, now, to the improved hour striking mechanism, an escapement segment 85 28 with teeth 29 engages pallets 30 and 31 on a member 32 that is pivoted on a stud 33 on the lower end of an arm 34 pivoted at 35 to the bearing plate 17 and placed under tension of a spring 36 which tends to force 90 the pallets toward and in engagement with the teeth 29. The spring 36 is secured at 37 to the bearing plate in which is a stop pin 38 that supports the spring against turning backward on its fastening screw or pin 37. 95 The segment 28 is on an arm 39 which is pivoted on a stud 40 held in the bearing plate 17. The arm 39 has an intermediate U-shaped portion 41 which carries the arm 39 clear of interference with the second-hand and its arbor —42— and underneath the arbors 21 and 14 to give it unrestricted clearance for its downward movement when set to strike as in Fig. 3. The arm 39, 41 is really a part of a bell crank lever, the 100 other arm of which is a stud 43 on a hub 44 that is mounted on the pivot 40. The arm 43 of this bell crank lever is held under tension of a spring 45 one end of which is attached to the arm 43 and the other end 110

attached to a stud 46 on the ring 15'. This spring tension holds the escapement normally raised against a stud 47 on the lug 14' and assists in actuating it after being "set" in operative position. The escapement segment is set, or lowered into operative position against the tension of the spring 45, by means of a bell crank lever having a rigid arm 48 and a flexible arm 49 that are pivoted at 50 on the plate 17. The flexible arm 49 is a comparatively rigid spring to the free end of which is pivoted at 51 a lighter and more flexible spring 52 which connects the arm 49 with the U 41 at 53. The lever 48, 49 and 52 is lowered or swung into operative position by means of a short arm or horizontal stud 54 on the arm 55 which extends from the hub 56 of the pinion 27. The latter is of the same size as the second pinion 22 and is therefore rotated at the same speed, that is, synchronously with the minute hand. A third bell crank lever with a power arm 57 and a load arm 58 is pivoted at 59 on the bearing plate 17 and serves to hold the pallets 30 and 31 out of engagement with the teeth 29 between the striking periods. This is accomplished by means of a circular disk 60 that is fast on the arbor 14 between the pinion 22 and the wheel 26 and engages a pin 61 which projects laterally from the end of lever arm 57 and rests on the edge of the disk. In the disk 60 is a recess 62, or cam dip, into which the pin 61 is admitted immediately before each striking takes place and in which it is held, by suitable elongation of the slot 62, until the striking is over. The bell clapper or hammer —63— is on a wire arm 64 which is an upward continuation of the member 32 carrying the pallets, and is balanced by a weight 65 on a similar arm 66 that extends downwardly from the member 32. At the moment when the pin 61 drops into the depression 62 to permit the lever arm 58 to yield its resistance to the bracket 34 under pressure of the spring 36, the engagement of the pallets with the teeth causes a quiver in the balanced hammer causing it to make a slight tap on the bell —67— as a warning that the clock is about to strike, thus, at night giving a sleepy person time to prepare for counting the strokes. Immediately thereafter, as shown in Fig. 3, the lever 55 is released from engagement with the lever arm 48 and the pull of the spring 45 upon the toothed rack 28 causes the arms 64 and 66 to swing to and fro one swing or blow for each successive tooth disengaged from the pallets. The upward pressure on the under side of the pallet 30 causes the upper end of the member 32 to swing outwardly which releases the pallet 30 and swings in the pallet 31 to engage a tooth and arrest the upward movement of the member 28 until the coun-

terweight resistance to the swing outward of the hammer equals the momentum and the reaction carries the hammer toward the bell to make the next strike.

The number of teeth to be thus disengaged from the pallets, or the distance downward that the upper end of the member 28 is moved from the stop 47 is determined by the "snail" 13 having the proper "step" therein engaged by a laterally projecting lug 68 on a horn 69 rising from the arm 39 at one end of the U 41. A similar lug 70 projecting from the other end of the U rests on top of the spring 49, the tension of which relative to the anchor stud 53 for the end of the spring 52, is upward, while the pull of the spring 52 is downward, which establishes equilibrium and holds the springs and the escapement in properly flexible relation, the lug 70 necessarily having a sliding engagement with the spring 49.

It will be noticed that the parts added to effect the striking are very simple elements from the manufacturer's standpoint, involving but a few cents extra cost and that the attachments are applicable to existing forms of clocks, so that non-striking clocks may be made to strike as in the case of the simple clock illustrated in this connection. The usual striking mechanism involves practically as much cost for spring and train of gears as the time mechanism, and it may therefore be said that my improved striking mechanism will reduce the cost of an hour striking clock by nearly one-half to say nothing about eliminating the trouble of winding the extra spring, or bearing its winding in mind.

As explained in the foregoing the striking mechanism is "cocked" or "set" by the wheel 24 of the train of gears which slows down to the speed of rotation of the hour hand the speed of the minute hand, namely, the train 22, 24, 25 and 26, and as the pinion 27 has the same number of teeth as the pinion 22 the arm 55 makes its complete revolution in the same period as does the minute hand. In Fig. 1 the cocking of the striking mechanism has been commenced, the lug or short arm 54 beginning its moving engagement with the lever arm 48 at the lower end of the latter which has been moved partly to the right as indicated by the space between the upper end of the rack 28 and its stop pin 47. The cocking movement of the arm 48 and its associated parts thus continues through an arc of approximately a one half hour's period, which imposes but little strain upon the power of the time mechanism. Of course by suitable curvature or curvatures of the lever arm 48 the setting or cocking of the striking mechanism may be prolonged throughout a larger part of the hour, and 54 may represent the position of an anti-friction roller. The

weight of the pendulum 65 relative to the weight of the hammer 63 regulates the rapidity of the hammer blows.

I claim as my invention—

- 5 The combination with a time keeping mechanism, of a pendulum balanced hour-striking hammer and pallets, a toothed segment to engage said pallets, means for bringing the latter into and out of engage-

ment with the teeth of said segment, means 10 for automatically adjusting by the clock movement the position of said segment, or to escape a given number of teeth, and a tension device tending to swing said segment in one direction.

In testimony whereof I have hereunto signed my name.

GUSTAF F. FRIBERG.
